Primary Examiner — Catherine Ho

(57) **CLAIM**

The ornamental design for a desktop sign, as shown and described.

DESCRIPTION

FIG. 1 is a front, top and right-side perspective view of the desktop sign showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom and right-side perspective view thereof;

FIG. 9 is a top perspective view thereof; and,

FIG. 10 is a bottom perspective view thereof.

The broken lines throughout the drawing figures depict portions of the desktop sign that form no part of the claimed design.

1 Claim, 10 Drawing Sheets
